DESIGN FOR A SALT-SHAKER.

No. 38,922.

Specification for Design.

Patented Dec. 3, 1907.

Application filed July 27, 1907. Serial No. 385,925. Term of patent 7 years.

To all whom it may concern:

Be it known that we, CLARENCE A. NELSON and CHARLES A. PAYNE, citizens of the United States, residing at the city of Utica, in the county of Oneida and State of New York, have invented a new, original, and ornamental Design for Salt-Shakers, of which the following is a specification, reference being had to the accompanying drawing, forming part thereof.

The drawing shows a side view in perspective of our new design.

We claim

The ornamental design for a salt shaker as shown.

CLARENCE A. NELSON.
CHARLES A. PAYNE.
